(57) **CLAIM**

The ornamental design for an oral irrigator, as shown and described.

DESCRIPTION

FIG. 1 is a front, top, right perspective view of an oral irrigator showing our new design;

FIG. 2 is a front view thereof;

FIG. 3 is a top view thereof;

FIG. 4 is a bottom view thereof; and,

FIG. 5 is a rear, bottom, right perspective view thereof.

The broken lines in the figures depict portions of the oral irrigator that form no part of the claimed design.
